FILING DEVICE

James R. Jones, Lakewood, and Carl L. Elofson,
Jamestown, N. Y., assignors to Art Metal
Construction Company, Jamestown, N. Y.

Application June 15, 1939, Serial No. 279,296

5 Claims. (Cl. 45—2)

This invention relates to filing devices for plans, photographs, tracings or analogous relatively large sheets, and a particular object of the invention is to provide a practical and desirable device in which a vertical filing case or container in which the sheets are maintained flat and prevented from crumpling or wrinkling, is combined with a table so as to enable the filed sheets to be readily pulled out onto or spread out on the table top, to facilitate their examination. Such a device, among other uses, is especially desirable for the filing of aerial agricultural photographs used for government crop allotment purposes, and the table with which the file case is combined provides an ample flat surface on which the photographs withdrawn from the file can be laid or spread out, and is thus a great convenience for the crop allotment clerk and the farmer or person who may have to consult him and have to examine the photographs.

Other objects of the invention are to provide a table having a file container arranged or suspended beneath the table top and accessible for the filing of the sheets in and their removal from the container through an opening in the table top provided with a cover which, when closed, is flush with other portions of the upper surface of the table top, whereby the full area of the top is available, when desired, as a surface on which to work, lay or spread out the photographs or sheets; also to provide a combined table and file case in which the sheets are filed vertically in removable pockets or folders which are adapted to be inserted into and removed from pocket supports or holders in the case, which retain the filed sheets flat in desired segregated groups and prevent them from crumpling or becoming creased or wrinkled.

Additional objects and advantages of the invention will appear from the following description of the preferred embodiment of the invention, shown in the accompanying drawings, and the novel features thereof are set forth in the appended claims.

In said drawings:

Fig. 1 is a perspective view on a small scale, of a combined table and filing device embodying the invention, showing the cover of the case opened and one of the sheet pockets raised and a sheet partially withdrawn from the same and resting and exposed on the table top.

Fig. 2 is a longitudinal, sectional elevation of the device taken on a vertical plane passing through the filing case.

Fig. 3 is an enlarged, broken transverse sectional elevation thereof on line 3—3, Fig. 2.

Fig. 4 is a fragmentary section similar to Fig. 2, on an enlarged scale.

Fig. 5 is a fragmentary, sectional elevation, 5 showing the support for holding the cover open.

The illustrated embodiment of the invention comprises a table 10 having a relatively long, narrow and deep rectangular filing case 11 arranged or suspended under the table top, which latter has an opening 12 therethrough conforming substantially in horizontal dimensions with the case, and a cover or lid 13 for the opening which, when closed, will occupy a position in the opening with the upper surface of the cover 15 flush with the upper surface of the table top, and which is preferably hinged to swing upwardly to open and afford access to the file case.

The table may be of usual or suitable form and construction, a flat-topped table of sheet metal construction being shown having a sheet metal top plate 14 with a linoleum or other sheet covering 15 and depending marginal flanges 16, and supporting legs 17 at the corners of the table. The table also preferably has the usual 20 skirt comprising side and end walls depending from the table top and set back or inwardly from the marginal top flanges. This skirt may be formed, as shown, by vertical sheet metal plates 18 extending from leg to leg at the front and rear 25 sides of the table, and similar vertical plates 19 extending from leg to leg at the ends of the table. As shown, these plates are provided with top flanges spot welded or otherwise suitably secured to the underside of the top plate 14, and 30 inturned bottom stiffening flanges, and the skirt plates are rigidly secured at their ends to the table legs, as by corner brackets welded to the 35 legs.

Preferably, the long front and rear edges of 40 the opening 12 in the table top are supported and braced by two parallel, vertical, sheet metal plates 20 which extend lengthwise of the table beneath the top plate 14 and are rigidly attached at their ends to the end skirt plates 19, as by 45 end flanges 21 on the supporting plates, spot welded to the skirt plates. The supporting plates 20 shown have outwardly bent top flanges 22 rigidly attached, as by spot welding, to the underside of the table top plate, and below the 50 latter, the plates 20 are offset toward each other providing upwardly facing supporting shoulders 23. The supporting plates are also preferably provided with out-turned bottom strengthening flanges 24. Thus, a stiff and rigid trussed frame 55

structure is provided from which the file can be suspended and supported, as will presently appear.

The file case may be of any suitable construction, but is preferably made of sheet metal. The vertical front and rear wall plates of the case are provided at their upper ends with out-turned flanges 25 which rest upon the supporting shoulders 23 and may be secured thereto by screws or 10 otherwise. At its narrow ends, the file case, as shown, has vertical extension plates 26 welded to the outside of the case end plates near their upper edges. These plates 26 extend upwardly to the table top and have out-turned, upper end flanges 27 which are attached, as by spot welding, to the underside of the top plate 14 at the end edges of the opening 12 in the top. The edges of the linoleum or top cover sheet at the opening 12 are preferably bound and protected 15 by vertical binding strips 28 which may be fastened to the upper portions of the supporting plates 20 and the extension end plates 26, with the upper edges of the strips engaging the edges of the cover sheet substantially flush with the 20 top surface of the cover sheet. By thus constructing and mounting the file case in the table, it is strongly and firmly supported and the table top and edges of the opening 12 are prevented from sagging or being deformed by the weight of the 25 file case and its contents.

The lid or cover shown for the opening 12 over the upper end of the file case is formed by a rectangular sheet metal plate 30 provided with downturned marginal stiffening flanges 31, and 30 this lid plate is covered by a linoleum or other cover sheet like that on the table top. Preferably, the edges of the lid cover sheet are protected by binding strips 32 secured to the marginal flanges of the lid and engaging the edges 35 of the cover sheet substantially flush with the top surface thereof. In its closed position, this lid is located within and forms a closure for the opening 12 in the table top, with the upper surface of the lid flush with the upper surface of 40 the table top, and the lid is preferably hinged at its long, rear edge to the table top by a piano hinge 33. Thus, when the lid is closed, it forms a portion of the table top flush with the upper surface of the other portions thereof, and it may 45 be swung upwardly and rearwardly and provided at one or each of its ends with a supporting arm 34 of any usual or suitable type adapted to support the lid in an upwardly and rearwardly inclined, open position, as indicated in Fig. 5.

The file case is preferably equipped with vertical pocket holders or supports 35 which provide separated compartments to receive vertical, removable folders or pockets 36 in which the photographs or other sheets are placed. The pocket 50 holders may be constructed and mounted to move horizontally toward and from each other in the case in any suitable manner adapted to form expandible compartments for receiving the removable file pockets or folders, but preferably 55 the opposite sides of each pocket holder or compartment are formed by flexible vertical strips 37 which are suspended from their ends and connected by bottom loops. Suitable springs 38 arranged between the strips of adjacent holders 60 urge the strips of each pocket holder toward each other to yieldingly press the filed sheets in the pockets together so as to hold the sheets flat and prevent them from sagging, crumpling or wrinkling in the file. As shown, the pocket holder strips 37 are suspended from horizontal rods 65

39 which extend lengthwise in the file case and project at their ends into horizontal guides 40 formed by the upper edges of the end walls of the file case, and cooperating guide strips 41 attached to the end extension plates 26 above the 5 rods. The rods are thus horizontally supported so as to be movable freely toward and from each other in their guides for the expansion and contraction of the pocket holders or supports.

When it is desired to refer to or examine a photograph or sheet in the file, the hinged lid or cover is swung upwardly and rearwardly and the pocket or folder containing the desired sheet is adapted to be pulled upwardly more or less completely out of its holder in the file case, and the desired photo or sheet laid over on the table top in front of the open lid or cover, as indicated in Fig. 1, or when desired, one or more of the photos and sheets can be removed from its or their pockets and spread out flat on the table 20 after again closing the hinged lid or cover.

We claim as our invention:

1. A filing device comprising in combination a table having a top with an opening therethrough and fixed frame skirt plates extending 25 from side to side below the top at the ends of the table, spaced supporting plates rigidly attached at their ends to said skirt plates and extending horizontally across the table beneath and supporting opposite side edges of said top opening, said supporting plates being vertically deep and forming strong rigid weight-supporting members and having offset shoulders at their inner sides, a file case arranged with its open upper end between said supporting plates and suspended therefrom by flanges at opposite sides 30 of the case seated on said shoulders, and a cover movable to open and close said top opening.

2. A filing device according to claim 1, in which the file case has plates at its opposite ends which extend upwardly beyond the tops of the sides of the case and are secured to the underside of the table top at the end edges of the top opening.

3. A filing device according to claim 1, in 45 which vertical extension plates at opposite ends of the file case extend up to and are secured to the edges of the table top at the opposite ends of the top opening, and have guide members adjacent the top of the file case for guiding movable file-supporting elements in the case.

4. The combination of a table comprising a metal top plate having an opening therethrough and fixed skirt plates extending horizontally beneath and attached to the top plate at opposite end portions of the table, spaced vertical supporting plates rigidly attached at their ends to said skirt plates and extending horizontally across the table beneath opposite side edges of said opening and having outwardly projecting top flanges on which said edges of the top opening are supported and secured, said supporting plates being vertically deep and forming strong rigid weight-supporting members and having inwardly offset shoulders, a file case arranged with its open upper end between said supporting plates and suspended therefrom by side flanges at the upper end of the case seated and secured on said shoulders, and a cover for opening and closing said case arranged to occupy a closed position in said top opening between said supporting plates above the shoulders thereof.

5. A filing device comprising in combination a table having supporting legs connected by a rigid horizontal top frame, and a top supported 75

on said top frame, said frame comprising rigidly connected frame members including flanged plates extending horizontally across the table in spaced apart relation immediately beneath the table top and forming vertically stiff weight-supporting members, and a vertically deep file case arranged with its open upper end between said supporting members and suspended from and wholly supported by said supporting mem-

bers, said top having an opening therethrough over said file case, the edges of the table top forming the opposite side edges of said opening being attached to and supported by said supporting members, and a cover movable to open and close said top opening.
